US00D941322S

(12) **United States Design Patent**
Nishikawa

(10) **Patent No.:** US D941,322 S
(45) **Date of Patent:** ** Jan. 18, 2022

(54) **DISPLAY SCREEN OR PORTION THEREOF
WITH GRAPHICAL USER INTERFACE**

(71) Applicant: **Nissan Motor Co., Ltd.**, Kanagawa (JP)

(72) Inventor: **Tomohiro Nishikawa**, Kanagawa (JP)

(73) Assignee: **Nissan Motor Co., Ltd.**, Yokohama (JP)

(**) Term: **15 Years**

(21) Appl. No.: **29/700,986**

(22) Filed: **Aug. 7, 2019**

(30) **Foreign Application Priority Data**

(57) **CLAIM**

The ornamental design for a display screen or portion thereof with graphical user interface, as shown and described.

DESCRIPTION

FIG. 1 is a perspective view of the first embodiment of a display screen or portion thereof with graphical user interface showing our new design;

FIG. 2 is a front view thereof;

FIG. 3 is a perspective view of the second embodiment of a display screen or portion thereof with graphical user interface showing our new design; and,

FIG. 4 is a front view thereof.

The broken line showing of a display screen or portion thereof is for the purpose of illustrating environmental structure and forms no part of the claimed design. The dot-dash line(s) define the bounds of the claimed design and form no part thereof.

1 Claim, 4 Drawing Sheets
